FLAME BAFFLE FOR PULVERIZED FUEL FURNACES

William K. Sanders, McGill, Nev., assignor of one-half to Edward J. Franklin, Salt Lake City, Utah

Original application June 6, 1931, Serial No. 542,600. Divided and this application July 28, 1932. Serial No. 625,481

2 Claims. (Cl. 122—235)

This invention relates to an improved flame baffle for pulverized fuel furnaces. The invention is particularly intended and adapted for use in connection with pulverized fuel furnaces for heating water tube boilers.

This application is a division of application Serial Number 542,600, filed by me on June 6, 1931.

The main object of the invention is to provide a means for preventing the flame and entrained particles of unburned or partly burned fuel from passing directly into the front or first pass of a water tube boiler when the fuel burner or nozzle is located at or near the upper portion of a furnace.

It has been found, in the operation of a furnace boiler and fuel burner combination such as above referred to that the draft pull maintained in the furnace has a tendency to divert the flame from the burner directly into the first bank of boiler tubes over the top of the refractory baffling provided in the bank of tubes, thus preventing the flame from maintaining the U-shaped trajectory which is deemed desirable. This diversion, or shortening, of the flame trajectory causes a considerable decrease in the length of time that the fuel remains in the furnace, and hence prevents the complete combustion of all particles of fuel while in suspension in the combustion space of the furnace. The result is, that unburned or partly burned particles of fuel are drawn directly into the gas passages between the boiler tubes causing a large loss in fuel and consequent clogging of the gas passages by reason of these fuel particles congealing and adhering to the boiler tubes.

My invention provides means whereby this difficulty is overcome and the flame from the burner is forced to pass downwardly into the combustion chamber of the furnace before it passes to the water tube boiler.

Another object of my invention is to provide means which will increase the radiant heat absorbent surface and also increase the evaporative effect of the boiler.

Other objects of my invention will appear hereinafter.

The accompanying drawing illustrates embodiments of my invention and referring thereto: Fig. 1 is a vertical section of one type of water tube boiler and furnace thereto showing my invention applied thereto.

Fig. 2 is a section on line 2—2 in Fig. 1.

Fig. 3 is a partial section of a baffle tube and the refractory covering blocks therefor.

In Figs. 1 and 2 my invention is illustrated as applied in connection with a boiler and furnace construction comprising a water tube boiler 1, a combustion chamber 2, and a burner 3 adapted for combustion of pulverized fuel such as coal dust or atomized fuel oil. The boiler is shown as comprising three banks of water tubes 4, 5 and 6 with baffle walls 7, 8 and 9 at the rear of each bank of water tubes, said baffle walls being staggered so as to insure that the product of combustion will pass in tortuous path and come into effective contact with substantially the entire area of each bank of water tubes, a connection being provided to flue 14 for conducting the combustion gases after they have passed the last bank of boiler tubes to a stack or other outlet means for same.

The water tubes are shown as connected at their lower ends to a water drum 10 and at their upper ends to drums 11, 12 and 13, and suitable piping is provided for connecting the upper and lower headers so as to provide for water circulation. In ordinary practice the circulation is effected by connections leading from the lower drum 10 to one of the upper drums or headers 75 for the water tubes by pipes extending above the combustion chamber 2, leaving the space between the burner 3 and the first bank of water tubes substantially unobstructed. With such an arrangement there is a tendency for the flames 80 to pass from the burner directly to the passage 15 above the first baffle wall 7 aforesaid instead of passing in the desired U-shaped course indicated by the arrows in Fig. 1.

To provide for deflection of the gases in the 90 desired course I provide a baffle extending downwardly from the top of the combustion chamber and comprising water tubes extending through the wall of the combustion chamber and connected for circulation of water therethrough and 95 refractory means covering said tubing so as to protect the same, the construction being such that all parts of such tubing within the combustion chamber are protected by said refractory covering from the heat of the burner.

The furnace roof 16 extends over the combustion chamber 2 and is shown as being composed of refractory material through which projects the fuel burner 3 fed by coal pipe 17. Across the width of the furnace is disposed a plurality of 105 bent tube elements 18 forming a baffle screen. These tubes 18 extend downwardly from an upper header 24 and are bent laterally at their lower portions so as to pass through the furnace side walls 19, terminating in the relatively ver- 110

tically disposed header members 20 to which a supply of relatively cooler water is furnished by means of the supply pipes 21, communicating by pipes 22 with the lower boiler drum 10.

5 The upper ends of the tubes 18 terminate in a discharge header 24, the relatively hotter water, together with such steam as has been generated in the tube system 18, being discharged to the boiler drum 11, through the tubes 25, or by any 10 other convenient means. The tubes 25 and headers 11, 12 and 13 may be covered in any convenient manner, as for instance by heat-resisting material 26, forming a continuation of the furnace roof insulating covering 16. The tubes 18, 15 may be covered with blocks 27 of any suitable material such as illustrated in Fig. 3, to provide a surface relatively impervious to the passage of flames or fuel particles therethrough, and to divert the flames downwardly from the fuel burner 20 or nozzle 3, into the U-shaped path previously described.

In the operation of the boiler, relatively cool water from the lower or mud drum 10 of the boiler flows through the piping 21 to the headers 20, thence through the tubes 18 and 25 to the boiler drum 11. With the described construction the flames from the burner 3 are prevented from taking the shorter path above referred to and are forced to pass first downwardly and then 30 upwardly before they pass through the first bank of water tubes, thereby insuring that the fuel particles will remain within the combustion chamber a sufficient time for effective combustion thereof and obviating the losses and difficulties above referred to. The deflection of the 35 products of combustion in this manner also insures that they will be brought into more effective contact with the first bank of water tubes, thereby increasing the evaporative effect. Additional evaporative effect is also secured by contact of the hot products of combustion with the water tubes 18 and by the heat absorbing and radiating action of the baffle wall mounted thereon.

45 I claim:

1. A water tube boiler and furnace construction comprising a combustion chamber provided with top and side walls and having an outlet passage at the upper portion of said chamber, a water tube boiler arranged to receive gases passing from said outlet passage, a burner adapted to direct flame into the upper part of said combustion chamber and a baffle extending downwardly from the top of the combustion chamber but leaving

an unobstructed space between it and the bottom of the chamber so as to prevent passage of flame from the burner directly to the said outlet, and to cause the flame to pass downwardly under said baffle and then upwardly to said outlet passage, said baffle comprising header means at the top of the combustion chamber and communicating with the upper part of the boiler, header means at the side of the combustion chamber communicating with the lower part of the boiler, said header means being outside the combustion chamber, water tubes extending downwardly from the header means at the top of the combustion chamber and having their lower ends bent laterally and communicating with the header means at the side of the combustion chamber so as to provide for circulation between the boiler and the water tubes through said header means, the respective ends of each water tube extending through the top and side walls of the combustion chamber to communicate with the respective aforesaid header means and refractory baffle means mounted on said water tubes to protect the same from the heat of the flame in the combustion chamber.

2. A water tube boiler and furnace construction comprising a combustion chamber having an outlet passage at the upper portion thereof, a water tube boiler arranged to receive gases passing from said outlet passage, a burner adapted to direct flame into the upper part of said chamber and a baffle extending downwardly from the top of the combustion chamber so as to prevent passage of flame from the burner directly to the said outlet passage, but leaving an unobstructed passage below said baffle through which the flame is deflected in passing to said outlet passage, said baffle comprising water tubes and refractory baffle means mounted on and covering said water tubes, a header extending above the combustion chamber and in communication with said water tubes and with the upper part of water tube boiler, headers at the respective sides of the combustion chamber and in communication with the lower part of the water tube boiler and with the water tubes in the baffle, said water tubes in the baffle extending downwardly from said upper header and bent laterally at their lower portions and extending through the side walls of the combustion chamber and communicating outside the combustion chamber with the respective headers at the sides of the combustion chamber.
